SLUG HANDLING DEVICES

James Ross Gentry, Oak Ridge, Tenn., assignor to the United States of America as represented by the United States Atomic Energy Commission

Application March 10, 1945, Serial No. 582,093

4 Claims. (Cl. 294—114)

This invention relates to article handling devices. More particularly, this invention concerns devices for handling containers filled with chemical materials referred to in this particular art as slugs.

In certain fields, particularly in some of the chemical and allied industries, it is necessary to handle small containers of hazardous materials. These containers or slugs, as they are termed herein, may be filled with various different chemical components. While these slugs are usually rather small in size, they are relatively heavy. Although they may be constructed of metal cases fully enclosing the materials, there possibly may be small ruptures in the casing and for various other reasons, the manual handling thereof even with heavy protective gloves is undesirable as this might bring the slugs into close proximity with the body of the handler thereby presenting possible dangers. These containers of materials or slugs of the class described herein, as will be pointed out, may be of various configurations, but for convenience of description and inasmuch as one of the most frequent types encountered is cylindrical in shape, this type is primarily considered herein. However, it is to be understood that the term container or slug is employed to embrace any of the usual configurations whether they be long or short cylinders, hexagonal, square, or other similar shapes.

The use of the slugs in such chemical processes and related subject matter forms no part of the present invention. The present invention is concerned with providing a device by which the articles of the class described may be, for example, picked up out of a liquid and inserted into another liquid or into a tank or other similar handling operation conveniently carried out without the operator coming into contact with the article handled or the liquid or other media into which it is introduced or from which it is removed. The details relative to the processing of the slugs and related information is the invention of others and is described in copending applications such as Seaborg and Thompson App. Ser. No. 519,714, filed January 26, 1944, now Patent No. 2,785,951, issued March 19, 1957, or in Raymond W. Stoughton application Ser. No. 570,803, filed December 30, 1944.

I have found devices particularly useful in handling such slugs without the attendant danger of permitting the slug to come into unduly close contact with the person, and by which the slug may be relatively conveniently removed from tanks, liquids, or other environments and moved to different environments.

This invention has for one object to provide an article handling device particularly suitable for handling containers of the class described containing certain chemical materials.

Another object is to provide a slug handling device.

Still another object is to provide a device of the class described whereby the article being handled may be kept at a suitable distance from the person.

Still another object is to provide a handling device of

2

the class described which is suitable for handling small containers of materials which may present hazards if permitted to come in contact with the body or too close to the body.

5 Another object is to provide a slug handling device which will function to handle small but relatively heavy metal containers of certain chemical materials.

Still another object is to provide a device of the class described by means of which the aforementioned type of container or slug may be picked up or released by the operator of the handling device.

A still further object is to provide a manually operated slug handling device.

Other objects will appear hereinafter.

15 I have found a device of the type described that is particularly suitable for handling articles containing chemical components which it is desired to keep away from contact with the operator, and may be comprised of an elongated handle provided with a mechanism which includes

20 gripping means such as pivoted jaws that will suitably grip the slug to be handled. In addition the weight of the slug being handled assists in the aforementioned gripping action. However, by application of counter force, the slug may be easily released.

25 For a complete understanding of the invention, reference will be made to the attached drawings forming a part of the present application.

Fig. 1 is a simple side elevation view for illustrating one type of slug or container referred to as handled by the device of the present invention.

30 Fig. 2 is a side elevation view of one species of handling device in accordance with the present invention.

Fig. 3 is a sectional view of this species taken on the line A—A of Fig. 2.

35 Fig. 4 is a side elevation view of still another species of device in accordance with the present invention.

Fig. 5 is a sectional view of this species taken on the line B—B of Fig. 4.

40 Fig. 6 is a side elevation view of still another species of construction.

Fig. 7 is a sectional view, on a larger scale, of a portion of the species of Fig. 6.

45 Referring now to Fig. 1, the slug or container 2 frequently required to be handled as herein described may be, as depicted, merely a cylindrical can much the same in shape as the usual metal can encountered ordinarily such as those which contain foodstuffs, lubricating oils, or many other materials. The primary difference would be that a slug might be several times longer than such ordinary cans or of a greater diameter, and of a different type metal, or sealed differently at the ends. However, for general considerations as to shape it may be regarded as analogous to such ordinary cans.

50 Referring now to Fig. 2, a slug 2 is shown held by a slug handling device of the present invention. Reference numeral 3 indicates the outside sleeve or housing for the device. A supported means 4 for an elongated hollow handle 5 is attached to the housing.

55 Referring to Fig. 3 which is a sectional view taken on the line A—A of Fig. 2, the parts already referred to have been indicated in this sectional view. Within the housing 3 there is positioned a movable sleeve 6 which is adapted to move upwardly or downwardly by the application of tension or the release of tension of the trip string 7. The downward movement of sleeve 6 is stopped by the shoulder 8 on the inner surface of housing 3.

60 Attached to the bottom of movable sleeve 6 are a plurality of pivoted gripping arms or jaws 9. These members are held by bolts, rivets, welding or the like, as at 10, to the movable sleeve 6. The gripping members 9 are held in an engaging position by means of springs 11 or equivalent means.

In normal position members 9 engage the slug as indicated in the drawing. By applying tension to the trip string 7 the gripping arms or jaws are moved upwardly to the disengaged position indicated in the dotted line showing.

Referring to Fig. 4, another species of construction is shown which is suitable for handling heavier slugs because of the longer spring members 31. The device of Fig. 4 is otherwise quite similar to the one already described. The heavier slug to be handled is indicated by reference numeral 22. The outer sleeve member or housing is indicated by reference numeral 23. Attached thereto is a suitable supporting means 24 for holding handle 25.

Referring to Fig. 5, which is a sectional view taken on the line B—B of Fig. 4, a movable inner sleeve 26 is provided. This sleeve may be moved upwardly by means of tension applied to the trip string 27. The movement of the sleeve downwardly is stopped by the cover 28. Pivoted gripping arms or jaws 29 are provided for engaging the slug. These members are connected by means of long springs, 31, to the cover 28.

In operation the springs hold the gripping members in engaging position, however, when tension is applied to the trip string 27 and cover 28 is raised, as shown in dotted line, the gripping members are brought into a disengaged position.

Referring to Fig. 6, the species of device here shown comprises the slug grasping mechanism 43, which may have attached thereto a long rugged handle 44. The mechanism 43 is flared as at 45 for ease in sliding the device over the top of a slug.

Referring now to Fig. 7, as shown in section, the mechanism 43 may be constructed of metal. Positioned on the side of the mechanism as at 46 is an opening which contains a gripping arm or jaw member 47. Teeth or other friction means are provided at 48. The member is pinned in a movable manner at 49 and is connected by rod 50 to a lever arrangement 51. This lever arrangement is supported in a movable manner by bracket 52. A trip rod or cable extending up the handle is provided at 53. Force applied to the parts for causing the jaw member to pivot inwardly is obtained by a spring as at 54. In this connection it will be understood that one end of spring 54 is secured to tubular socket member 43 and the other end is joined to pivoted lever 51, so that as the lever is swung about its pivot by rod 53, the spring 54 is placed under tension, and will tend to return the lever 51 to its original position when the upward force on the rod 53 is removed or relaxed.

As apparent from the drawing the spring holds the gripping arm or jaw member 47 inwardly. Therefore, when the device is pushed over the top of a slug, the teeth 48 securely hold the slug in the handling device. The slug may be moved about and handled as desired. The slug may be released from the device by pulling the trip rod or cable 53 which functions through the lever 51 and rod 50 to disengage the ratchet 47 or similar gripping member.

From the foregoing it will be seen that I have provided a simple but efficient device which may be used for handling slugs. The device is easy to push on to the slug and quickly grips it. It will be noted that I have provided a device in which there are means for gripping and releasing a slug without the necessity for touching the same; said means involving pivoted jaws the gripping action of which is assisted by the weight of the slug.

From the several species described, it may be seen that my invention is susceptible of various embodiments. While the species described are tubular or cylindrical inasmuch as the particular type of slug to be handled

was a cylindrical slug, the present species of the devices may be used for handling hexagonal or other shaped slugs. Or tubular shape of the device may be modified for rendering it specifically suitable for handling special slug shapes. Likewise other changes will be apparent.

It is to be understood that all matters contained in the above description and examples are illustrative only and do not limit the scope of this invention, as it is intended to claim the invention as broadly as possible in view of the prior art.

I claim:

1. Apparatus for handling slugs comprising a housing, supporting means for a handle attached to the housing, a handle connected thereto, a movable sleeve positioned within said housing, said sleeve being adapted to movement up and down within said housing, means associated with the movable sleeve to stop the downward movement thereof, a plurality of jaw members connected with said movable sleeve and held under tension for slug engagement, said jaws being adapted to movement into a disengaged position by upward movement of said movable sleeve.

2. Apparatus for handling slugs comprising a tubular member, supporting means for an elongated handle attached to the tubular member, an elongated handle connected thereto, a movable sleeve positioned within said tubular member, said sleeve being adapted to movement up and down within said tubular member, means carried by the movable sleeve to stop the downward movement thereof, a plurality of pivoted jaw members connected with said movable sleeve and held under tension for slug engagement, said jaw members being adapted to movement into a disengaged position by upward movement of said movable sleeve.

3. Apparatus for handling slugs comprising a tubular member, supporting means for an elongated handle attached to the tubular member, an elongated handle connected thereto, a movable sleeve positioned within said tubular member, said sleeve being adapted for movement up and down within said tubular member, an annular shoulder on the inner surface of said member adapted to cooperate with said movable sleeve to stop the downward movement thereof, a plurality of pivoted jaw members connected with said movable sleeve and held under tension for slug engagement, said jaw members being adapted for movement into a disengaged position by upward movement of said movable sleeve.

4. Apparatus for handling slugs comprising a tubular member, supporting means for a handle attached to the tubular member, an elongated handle connected thereto, a movable sleeve positioned within said tubular member, said sleeve being adapted for movement up and down within said tubular member, means carried by the upper portion of the movable sleeve to stop the downward movement thereof, a plurality of pivoted jaws connected with said movable sleeve and held under tension by relatively long springs for slug engagement, said jaws being adapted for movement into a disengaged position by upward movement of said movable sleeve.
